UNITED STATES PATENT OFFICE.

FRANK WIGGINS, OF KNOXVILLE, TENNESSEE.

INSTRUMENT FOR HANDLING DENTAL CLAMPS.

Application filed April 6, 1922. Serial No. 550,160.

To all whom it may concern:

Be it known that I, FRANK WIGGINS, a citizen of the United States, residing at Knoxville, in the county of Knox and State 5 of Tennessee, have invented certain new and useful Improvements in Instruments for Handling Dental Clamps, of which the following is a specification.

My invention relates to a dental instrument, and has particular reference to such an instrument designed specifically for use in connection with the matrix and matrix holder, shown in United States Patent No. 1,378,748, issued to me under date of May 15, 1921.

The matrix band shown in my Patent No. 1,378,748, above referred to, is adapted to substantially completely surround the tooth, such as a posterior tooth, and such band is 20 provided with outwardly projecting extensions or prongs, which engage within notches formed in a matrix holder or clamp. This matrix holder or clamp is designed to be arranged wholly within the mouth, between the gum and the cheek, and assumes 25 generally a vertical position. This leaves the top of the matrix band and of the filling entirely uncovered, in order that the corresponding tooth may be brought in proximity to a tooth being filled, and the proper 30 impression made in the filling.

Prior to my invention of the matrix and matrix holder, no device had been produced which would remain between the gum and 35 the cheek, beneath the top of the matrix band, and not interfere with the closing of the mouth. The holders in use prior to my patented matrix and matrix holder, extended over the tooth, and thus prevented the 40 closing of the mouth.

In accordance with the present invention, I have provided an instrument for manipulating the matrix holder or clamp, shown in my Patent No. 1,378,748, in placing the 45 holder upon the matrix band, and removing the same therefrom.

As the matrix holder or clamp is arranged wholly between the gum and cheek, and does not extend over the teeth the instrument 50 must possess certain characteristics, not required in connection with instruments for manipulating the clamps of the prior art, excepting that of Patent No. 1,378,748. The instrument must be flat at its forward end 55 so that it may pass between the gun and cheek, and be adapted to engage and hold

the spaced arms of the matrix holder or clamp. The instrument must be reversible for use upon either side of the cheek, in connection with the upper or lower teeth. 60

An important object of the invention is to provide a device of the above mentioned character, which is extremely simple in construction, strong and durable.

Other objects and advantages of the invention will be apparent during the course of the following description.

In the accompanying drawings forming a part of this specification and in which like numerals are employed to designate like 70 parts throughout the same.

Fig. 1 is a side elevation of a dental instrument embodying my invention, showing the same in use, in connection with the matrix holder engaging the matrix band upon the lower tooth.

Fig. 2 is a similar view with the matrix band and holder carried by the upper tooth, upon the same side of the face.

Fig. 3 is a similar view, showing the instrument inverted, and used in connection with the matrix band and holder carried by the lower tooth on the opposite side of the face.

Fig. 4 is a perspective view of the forward end of the instrument, and

Fig. 5 is a perspective view of the matrix band.

In the drawings, wherein for the purpose of illustration is shown a preferred embodiment of my invention, the numeral 10 designates a matrix band, preferably formed of a thin metal strip, sufficiently stiff for ordinarily retaining its shape, but sufficiently flexible to permit of the same being burred down to closely contact with the wall of the tooth, and conform to the curvature of the wall. The matrix band is adapted to pass between two of the adjacent teeth, with its ends slightly overlapping, preferably upon the outside or buccal wall of the tooth. The matrix band is provided at points near and spaced from its ends with curved or crescent shaped openings 11, stamped therein, forming outwardly bent attaching elements or teeth 12, preferably integral with the matrix band. These attaching elements or teeth are arranged upon the outer side of the tooth.

The resilient matrix holder or clamp comprises a U-shaped body portion 13 including an intermediate yielding portion 14. The

arms of the U-shaped body portion have their upper portions twisted and are arranged in a plane at substantially a right angle to the body portion 14. It is therefore obvious that the arms do not yield locally, when spread, but that the body portion 14 performs the yielding function. The upper ends of the arms are bent transversely and inwardly into flat jaws 15, having recesses or notches 16, for the reception of the elements or teeth 12. The U-shaped body portion is tensioned to swing inwardly.

The foregoing description is virtually a copy of the description of the matrix band and holder, in Patent No. 1,378,748.

The instrument which I have designed to be used specifically with the matrix holder, comprises a pair of oppositely arranged handles 17, preferably longitudinally curved to fit in the hand. These handles are non-crossing, and are pivotally connected at 18. The handles 17 continue in advance of the pivot 18 in the form of longitudinal extensions 19, having transverse extensions 20, disposed at substantially a right angle thereto.

Particular attention is called to the fact that the handles 17, extensions 19 and transverse extensions 20 are all arranged in the same plane, and that the structure is generally flat. This is essential, as it permits of the instrument being inserted in the mouth between the gum and the cheek. As shown more clearly in Fig. 4, the transverse extensions 20 are provided at or near their free ends with lateral projections 21, arranged at a right angle thereto.

The transverse extensions 20 are normally retained spaced in substantially parallel relation, and this may be effected by a leaf spring 22, secured to one handle at 23, while its free end slidably contacts with the other handle. The spring 22 is properly tensioned to normally hold the transverse extensions 20 in the spaced parallel relation.

In the use of the instrument, the lateral projections 21 are inserted within and between the arms of the matrix holder 13, and contact therewith. The matrix holder will now remain upon the projections 21 and the forward end of the instrument, carrying the matrix holder, may be inserted within the mouth between the gum and cheek. When in the mouth, a slight pressure upon the handles 17 will further spread the transverse extensions 20, so that the notches 16 may engage with the teeth 12. By moving the handles 17 outwardly slightly, the transverse extensions 20 may be brought together, and the matrix holder will remain locked to the matrix band. A similar operation is performed in removing the matrix holder

from the matrix band. This instrument may be employed upon either side of the mouth, as it may be inverted, and in either inverted position, it may be employed to attach the matrix holder to the matrix band upon the upper or lower tooth.

It is to be understood that the forms of my invention herewith shown and described are to be taken as preferred examples of the same, and that various changes in the shape, size, and arrangement of parts, may be resorted to, without departing from the spirit of my invention or the scope of the subjoined claims.

Having thus described my invention, I claim:

1. The combination with a matrix band provided near its ends and upon its outer side with extensions, of a resilient holder embodying spaced arms, said arms having notches to interlock with the extensions, and an instrument to expand the arms of the holder, said instrument comprising pivoted handles carrying forward longitudinal extensions having transverse extensions, the longitudinal and transverse extensions being in substantially the same plane, the transverse extensions being provided with lateral projections to engage within and between said spaced arms.

2. An instrument to be inserted within the mouth between the gums and cheek for manipulating a clamp, said instrument comprising a pair of spaced pivoted handles provided with longitudinal extensions projecting beyond the pivot, said longitudinal extensions having transverse extensions, the longitudinal and transverse extensions being arranged in substantially the same plane and form a generally flat structure, and lateral projections carried by the transverse extensions to engage with the clamp.

3. An instrument for insertion within the mouth between the gums and cheek, comprising a pair of spaced pivoted handles having longitudinal extensions projecting forwardly beyond the pivot, said longitudinal extensions having transverse extensions, the forward portion of the handles, the longitudinal extensions, and the transverse extensions being arranged in substantially the same plane for forming a generally flat structure, said transverse extensions being normally spaced and provided at their ends with lateral projections, which engage with the clamp, and a leaf spring arranged between said handles and tensioned to normally retain said handles in such a position that the transverse extensions are retained spaced.

In testimony whereof I affix my signature.
FRANK WIGGINS.
